ABSTRACT

An adapter for converting a standard low pressure pilot burner for use with a high pressure gas supply including a fitting adapted to engage tubing for supplying the gas under high pressure and an orifice member of the pilot burner, the fitting carrying a pair of pressure reducing orifices interconnected by an elongated passage through the fitting.

ADAPTER FOR CONVERTING LOW PRESSURE PILOT BURNER FOR USE WITH HIGH PRESSURE GAS SUPPLY

BACKGROUND OF THE INVENTION

1. Field of the Invention

The present invention pertains to pilot burners and, more particularly, to a pilot burner adapted to permit utilization of pilot burners with gas supplied at high pressures.

2. Discussion of the Prior Art

As is well known, many gas operated appliances including a main burner normally utilize a pilot burner to provide an ignition flame thereby rendering the burner continuously in condition for operation. Most gas supply lines utilized for such appliances deliver gas at low pressures, and standard pilot burners are designed for operation with gas supplied at such low pressures in order to provide a pilot flame of predetermined size.

Recently, the number of gas appliances being installed in multi-unit buildings, sometimes referred to as high rise apartments or office buildings, has substantially increased. It is desirable to utilize high pressure gas supplies for such buildings in order to provide adequate service and to reduce construction costs; however, standard low pressure pilot burners cannot properly operate under such high pressure conditions. Thus, the problem exists in the gas appliance field of having to vary construction of appliances, particularly pilot burners, dependent upon where the appliance is to be installed.

At first glance, the above described problem appears to be of a simple nature and easily solved; however, attempts to construct an adapter to permit use of standard low pressure pilot burners with high pressure gas supplies have not met with success in that there are practical limitations with respect to producing extremely small pressure reducing orifices, such adapter must preferably function for use with non-candling tab type standard pilot burners thereby preventing the use of extremely long adapter passages, cost and complexity must be kept at a minimum, and installation must be facilitated in order to keep labor costs at a minimum.

SUMMARY OF THE INVENTION

Accordingly, it is an object of the present invention to construct an adapter for use with a standard low pressure pilot burner in order to convert such pilot burner for use with a high pressure gas supply.

The present invention is generally characterized in a pressure reducing adapter for converting a low pressure pilot burner for use with a high pressure gas supply, the pressure reducing adapter including a fitting adapted to be disposed between tubing for supplying the high pressure gas and an orifice member of the pilot burner and having an elongated passage therethrough, and a pressure reducing orifice carried by the fitting in communication with the passage.

A further object of the present invention is to construct a pilot burner adapter for modifying a standard pilot burner for low pressure gas of the inches of water column order to operate with high pressure gas of the pounds per square inch order.

Another object of the present invention is to provide an adapter for reducing the pressure at a pilot burner orifice sufficiently such that the pressure at the pilot

burner orifice corresponds to the nominal supply pressure for an inches of water column pilot burner.

The present invention has another object in that noise accompanying the reduction of pressure from a high pressure gas supply to a low pressure required for a standard pilot burner is reduced to a minimal level.

A further object of the present invention is to construct a pressure reducing adapter for use with a standard low pressure pilot burner such that the adapter may be easily installed and is composed of a minimal number of parts thereby reducing labor and material costs.

Some of the advantages of the present invention over previous attempts to reduce the pressure at a pilot burner are that the components of the adapter of the present invention are of a simple design and may be easily manufactured, the adapter of the present invention may be utilized with non-candling tab type standard pilot orifice members and the adapter may be installed directly upstream of the pilot orifice member thereby facilitating installation thereof.

Other objects and advantages of the present invention will become apparent from the following description of the preferred embodiment taken in conjunction with the accompanying drawing.

BRIEF DESCRIPTION OF THE DRAWING

The FIGURE is a broken side elevation, partly in section, of a pilot burner adapter according to the present invention in combination with a main burner.

DESCRIPTION OF THE PREFERRED EMBODIMENT

The pilot burner adapter is illustrated in the FIGURE in combination with a main burner 10 having a bracket 12 extending therefrom for supporting a pilot burner assembly 14. Bracket 12 has an externally threaded nipple 16 depending therefrom adapted to engage an internally threaded nut 18. Nipple 16 has a cylindrical bore 20 extending from an outer end 22 thereof to a flared inner end 24.

Nut 18 has a cylindrical bore 26 therethrough to receive a piece of tubing 28 adapted to supply gas under high pressure to the burner assembly 14. A beveled wall 30 extends from bore 26 to an internally threaded wall 32 which engages nipple 16. Tubing 28 carries an annular ferrule 34 adjacent an end 36 thereof; ferrule 34 having a generally triangular configuration in cross section with opposite sides 38 and 40 meeting at a flat apex.

An orifice member 42 has a curved head 44 extending slightly above bracket 12 with a centrally disposed orifice 46 therein to permit gas effluence to support a pilot flame. Head 44 is aligned with outer end 22 of bore 20 through nipple 16 and terminates in a cylindrical wall 48 which extends through bore 20 and has a flared skirt 50 extending outwardly therefrom to engage the flared end 24 of bore 20.

As thus far described, the pilot burner assembly may be assembled for use with a low pressure gas supply by tightening nut 18 such that surface 40 of ferrule 34 seals against skirt 50 of orifice member 42 and surface 38 engages beveled wall 30 to provide a gas seal between tubing 28 and orifice member 42. Accordingly, low pressure gas from tubing 28 will escape through orifice 46 to support the pilot flame.

An adapter for modifying the pilot burner assembly 14 as thus far described for use with a high pressure gas supply is indicated generally at 52 and includes a fitting 54 having a central cylindrical body 56 with a neck 58 having an outer diameter substantially the same as the inner diameter of wall 48 of the orifice member 42. The outer surface of fitting 54 around body 56 defines an outwardly extending frusto-conical shoulder 60 adjacent neck 58, the configuration of shoulder 60 corresponding to the configuration of flanged end 24 of nipple 16 and skirt 50 of orifice member 42. An annular recess 61 is formed in fitting 54 within an annular collar or flange 62 depending from body 56. Flange 62 has a beveled edge 63 for sealably engaging surface 40 of ferrule 34.

Projections 64 and 66 extend centrally from opposite ends of body 56 and have grooves formed therearound by annular ribs 68 and 70, respectively. A passage 72 extends longitudinally through the center of body 56 and projections 64 and 66 to permit gas to flow through fitting 54. A small cup-shaped orifice member or spud 74 having a central orifice 76 is press fitted and rolled on projections 64 and held in place by a dimple engaging the groove formed by rib 68, and a similar small cup-shaped orifice member or spud 78 having a central orifice 80 is press fitted and rolled on projection 66 and held in place by a dimple engaging the groove formed by rib 70.

In assembly, the fitting 54 is positioned between the orifice member 42 and tubing 28 such that shoulder 60, skirt 50 and flared end 24 of nipple 16 are in tight engagement, and the tubing 28 forms a gas seal with fitting 54 due to engagement of surface 40 of ferrule 34 with beveled edge 63 of flange 62 of the fitting. With nut 18 screwed onto nipple 16, the entire pilot burner assembly is tightened to provide the required gas seal in order to prevent escaping gas.

The adapter 52 is, thus, easily assembled with a standard low pressure pilot burner in that the adapter need only be inserted between the standard tubing and pilot orifice member. That is, the nut 18 need only be loosened to separate the tubing 28 from the orifice member 42 and the adapter 52 inserted therebetween to convert a standard low pressure pilot burner for use with a high pressure gas supply. Tubing 28 desirably has end 36 chamfered to assure bottoming of the tubing in recess 61.

Once assembled the adapter 52 operates as a pressure reducer in that the high pressure of the gas upstream of the adapter in tubing 28 is reduced as gas flows through orifice 80, passage 72 and orifice 76 of the adapter 52. Accordingly, the pressure of the gas in the chamber 82 defined between adapter and orifice member 42 is reduced to the nominal low pressure required to provide a predetermined pilot flame fed by the effluence of gas through pilot orifice 46. The combination of pressure reducing orifices 76 and 80 and the length of passage 72 provide the required reduction in pressure from pounds per square inch to inches of water column while maintaining noise at a low level.

In order to further reduce the noise level, the pressure reducing orifices of the adapter may be displaced from the longitudinal alignment shown in the FIGURE such that the pressure reducing orifices are not aligned; and, furthermore, one or both of the pressure reducing orifices can open at an angle to the longitudinal axis of the passage 72 through the fitting.

The pressure in the chamber 82 between the adapter 52 and the orifice member 42 can be controlled by varying the size of the pressure reducing orifices 76 and 80. For example, when the supply pressure in tubing 28 is 10 psi, the pressure in chamber 82 can be reduced to 16.9 in. of water column by providing pressure reducing orifices 76 and 80 each with a diameter of 0.010 in. with pilot orifice 46 having a diameter of 0.016 in.; and, with the supply pressure remaining at 10 psi, the pressure in chamber 82 can be reduced to 7.7 in. of water column by providing pressure reducing orifices 76 and 80 with diameters of 0.010 in. and 0.008 in., respectively, while retaining the diameter of the pilot orifice 46 at 0.016 in.

15 The pilot burner adapter of the present invention may be provided with any suitable external configuration in order to cooperate with various pilot burners, it being of primary importance only that the adapter have an elongated passage and a pressure reducing orifice to reduce gas pressure in the tubing prior to supply to the pilot orifice. That is, while the external configuration of fitting 54 provides an advantageous gas seal with the pilot orifice member 42 and tubing 28, other configurations may be utilized dependent upon the configuration 20 of the pilot burner support bracket and nipple and the fastening nut.

25 Inasmuch as the present invention is subject to many variations, modifications and changes in detail, it is intended that all matter described above or shown in the 30 accompanying drawings be interpreted as illustrative and not in a limiting sense.

What is claimed is:

35 1. A pressure reducing adapter for converting a low pressure pilot burner for use with a high pressure gas supply, the pilot burner including an orifice member adapted to receive gas through tubing means; said adapter comprising a fitting having a central body adapted to be disposed between the tubing means and the orifice member of the pilot burner and having first and second projections extending from opposite ends of said central body with an elongated passage extending through said central body and first and second projections, a first cup-shaped orifice member engaging said first projection and carrying a first pressure reducing orifice, and a second cup-shaped orifice member engaging said second projection and carrying a second pressure reducing orifice.

40 2. The pressure reducing adapter as recited in claim 1 wherein said first and second pressure reducing orifices are aligned with said passage.

45 3. A pilot burner assembly for use with a high pressure gas supply comprising tubing means adapted to supply gas under high pressure;

50 55 5. A pressure reducing adapter means interconnecting said tubing means and said pilot orifice means including a fitting engaging said tubing means with a gas seal, said fitting having a central body with first and second projections extending from opposite ends of said central body, elongated passage means extending through said central body and first and second projections, a first cup-shaped orifice member engaging said first projection and carrying a first pressure reducing orifice, and a second cup-shaped orifice member engaging said second pro-

jection and carrying a second pressure reducing orifice.

4. The pilot burner assembly as recited in claim 3 wherein said pilot orifice means includes a member having a head with a pilot orifice therein and a cylindrical wall extending from said head and terminating at a flared skirt, and said central body of said fitting has a frusto-conical shoulder engaging and mating with said skirt.

5. The pilot burner assembly as recited in claim 3 wherein said fitting has an annular recess therein receiving said tubing means and an annular flange surrounding said recess and engaging said tubing means to provide a gas seal.

6. The pilot burner assembly as recited in claim 5 wherein said tubing means includes a ferrule disposed around the end thereof and having a surface for engaging said flange of said fitting.

7. The pilot burner assembly as recited in claim 6 and further comprising a nipple having a central bore there-through receiving said pilot orifice member and being externally threaded, and an internally threaded nut engaging said nipple, said fitting being disposed within said nut whereby the engagement of said nut and said nipple tightens said pressure reducing adapter means with said tubing means and said pilot orifice means.

8. An adapter for a pilot burner which includes a low pressure orifice means adapted for receiving gas through tubing means, comprising

a fitting having a central body adapted to be disposed between the tubing means and the low pressure orifice means and having an elongated passage there-through,

a first orifice member on the fitting having a first reducing orifice communicating from the tubing means to one end of the elongated passage, and a second orifice member on the fitting having a second reducing orifice communicating from the other end of the elongated passage to the low pressure orifice means,

said passage between the one and other ends having a length which with the first and second reducing orifices provides a reduction in pressure from the tubing means to the low pressure orifice means while maintaining noise at a low level.

9. A pressure reducing adapter for converting a low pressure pilot burner for use with a high pressure gas supply, the pilot burner including a threaded nipple, a low pressure orifice member having a skirt for extending from the nipple, an annular ferrule on an end of a high pressure gas supplying tube and a threaded nut surrounding the tube and the ferrule and adapted to screw to the nipple and to tighten the ferrule against the skirt to seal the tube to the low pressure orifice member; said adapter comprising

a fitting adapted to be sealingly tightened by the nut and nipple between the tube and the low pressure orifice member, said fitting having (a) a shoulder for engaging the skirt, (b) an annular flange for engaging the ferrule, and (c) an elongated passage between the tube and the low pressure orifice member; and

pressure reducing orifice means carried by the fitting in communication with the passage.

10. A pressure reducing adapter as recited in claim 9 wherein said pressure reducing orifice means includes

a first pressure reducing orifice at one end of the passage, and

a second pressure reducing orifice at the other end of the passage.

11. A pressure reducing adapter as recited in claim 9 wherein

the skirt is flared, the shoulder is frusto-conical, and the annular flange terminates in a beveled edge for engaging the ferrule.

12. A pilot burner assembly for use with a high pressure gas supply comprising tubing means adapted to supply gas under high pressure,

low pressure orifice means for establishing a pilot flame with gas under low pressure, a pressure reducing adapter having a central body interconnecting the tubing means and the low pressure orifice means,

said adapter having an elongated passage extending between the tubing means and the low pressure orifice means,

a first orifice member on the adapter having a first reducing orifice communicating from the tubing means to one end of the elongated passage, a second orifice member on the adapter having a second reducing orifice communicating from the other end of the elongated passage to the low pressure orifice means, and

said passage between the one and other ends having a length which with the first and second reducing orifices provides a reduction in pressure from the tubing means to the low pressure orifice means while maintaining noise at a low level.

13. A pilot burner assembly for use with a high pressure gas supply comprising

an annular ferrule on an end of a high pressure gas supplying tube;

a threaded nipple;

a low pressure orifice member having a skirt for extending from the nipple;

a threaded nut surrounding the tube and the ferrule and adapted to screw to the nipple and to tighten the ferrule against the skirt to seal the tube to the low pressure orifice member;

a fitting adapted to be sealingly tightened by the nut and nipple between tube and the low pressure orifice member, said fitting having (a) a shoulder for engaging the skirt, (b) an annular flange for engaging the ferrule, and (c) an elongated passage between the tube and the low pressure orifice member; and

pressure reducing orifice means carried by the fitting in communication with the passage.

14. A pilot burner assembly as recited in claim 13 wherein said pressure reducing orifice means includes a first pressure reducing orifice at one end of the passage, and a second pressure reducing orifice at the other end of the passage.

15. A pilot burner assembly as recited in claim 13 wherein

the skirt is flared, the shoulder is frusto-conical, and the annular flange terminates in a beveled edge for engaging the ferrule.
